UNITED STATES PATENT OFFICE.

WILLIAM WESTBURY, OF OKMULGEE, OKLAHOMA.

GLASS-CYLINDER-CAPPING APPARATUS.

1,203,826.

Specification of Letters Patent.

Patented Nov. 7, 1916.

Application filed September 20, 1915. Serial No. 51,737.

To all whom it may concern:

Be it known that I, WILLIAM WESTBURY, a citizen of the United States, residing at Okmulgee, in the county of Okmulgee and 5 State of Oklahoma, have invented certain new and useful Improvements in Glass-Cylinder-Capping Apparatus, of which the following is a specification.

This invention relates to glass cylinder 10 capping apparatus, and has for its object to produce a horse provided with a plurality of electrical capping-off devices, adjustable toward and from the cylinder-supporting arms of the horse and also adjustable independently or together longitudinally of the horse, the first-named or transverse adjustment of the devices accommodating the apparatus to cylinders of different diameter, and the other or longitudinal 15 adjustments enabling the attendant to more quickly set the capping devices at the points where it is desired to sever or cut a cylinder.

With this general object in view the invention 20 consists in certain novel and peculiar features of construction and combinations of parts as hereinafter described and claimed; and in order that the invention may be fully understood reference is to be had to the accompanying drawing, in which,

Figure 1, is a central vertical section of a glass cylinder capping apparatus taken on the line I—I of Fig. 2, with certain central parts in elevation. Fig. 2, is an enlarged 25 fragmentary end view of the apparatus. Fig. 3, is a full sized view of a portion of one of the arms carrying a capping off wire and guide mechanism therefor.

Referring to the drawing in detail 1 is a 30 floor or other foundation for a series of V-shaped standards 2, and secured in the upper ends of said standards is a bar 3 provided with a set of laterally projecting inverted-arch arms 4 which serve as a support 35 or cradle for a glass cylinder 5 preliminary to and during the capping operations thereon. If desired the standards 2 may be equipped with a second set of the arms 4, as shown in the drawing. The arms 4 are 40 preferably pivoted on bar 3 and are prevented from dropping down to a vertically pendant position by underlying rods 6, preferably secured to the standards 2, in any suitable manner.

7 indicates a series of plates or lugs projecting rigidly upward from bar 3, and

carrying a rod 8 forming a journal or pivot for a set of arms 9, these arms preferably being slightly arched. If the apparatus is provided with a double set of arms 4, it 60 should likewise be provided with a double set of arms 9, as shown. The rod 8 is longitudinally adjustable for the purpose of simultaneously shifting all the arms 9 relative to cylinder 5, as it is easier to make the 65 adjustment described than it would be to shift the cylinder, it being understood that the cylinder is placed upon the horse with less care as to its position than as to its safety against breakage. It is therefore desirable to be able to shift or slide rod 8 longitudinally so as to position the set of arms thereon with reference to avoidance of waste 70 of glass.

For convenience in adjusting the apparatus to sever cylinders in sections of different lengths, the arms 9 are so fitted upon the rod 8 as to be adjustable longitudinally thereon, the said arms being pivoted on said rod so that they may be swung upward to 75 a substantially vertical position to enable the attendants to lower a glass cylinder upon arms 4, and then swung downward to operative position, as shown by Fig. 2.

The free end or extremity of each arm 80 9 is preferably reduced in thickness at 10, and each arm is equipped with a wire guide 11, preferably formed by suitably stamping a piece of sheet metal and then bending it to provide a pair of similar or substantially 85 T-shaped sides, the stem portions of which fit against opposite sides of the recess portion 10 of the arm, one of the said stem portions being longer than the other and receiving a pivot bolt 13 secured in place by 90 means of a nut 14, the latter also co-operating with the pivot bolt in securing a feed wire 15 to the arm and in electrical connection with the wire guide 11. Journaled at opposite ends of the wire guide and between 95 the sides thereof is a pair of guide sheaves 16 and 17 for a wire W.

18 is a metal bar secured to the lower edge of arm 9 and attached at one end to a second feed wire 19, the opposite end of said bar 100 extending downward obliquely as at 20, and having an eye or opening 21 near its free end through which the said wire W extends, one end of the wire being fastened to an anchor or screw 22, and the other end being 105 free, a fiber block or other insulating device 23 being secured to the metal bar 18 to pre-

vent any chance of contact between said bar and the wire guide 11.

Assuming that a glass cylinder has been placed upon the horse, the operator swings an arm 9 downward and at the same time grasps the wire W and draws it around the cylinder and then upwardly and around the sheaves 16 and 17, and at the same time exerting a pull on the free end of the wire at the point where it extends from the sheave 17 so as to draw the wire tightly around the cylinder and at the same time rock the guide until its lower end abuts against the insulating block 23, in which position it will be observed the wire completely encompasses the cylinder except for a short gap between the free end of bar 18 and the sheave 16. If the current is on it will by flowing from bar 18 to sheave 16 over the cylinder-encompassing wire, heat such wire and effect or aid in effecting the severance of the cylinder, in a well known manner. The operator will repeat the operation described at each point where the cylinder is to be cut, and thereby effect the capping of the cylinder in much quicker time than where it is necessary for the operator to shift his capping wire and accessories along the cylinder.

From the above description it will be apparent that I have produced glass cylinder capping apparatus which embodies the features of advantage enumerated as desirable in the statement of the object of the invention, and while I have illustrated and described the embodiment of the invention which I now deem the best and most practical embodiment, it will be understood, that I reserve the right to make such changes in the form, proportion, detail construction and arrangement of the parts as properly fall within the spirit and scope of the appended claims.

I claim:

1. In a glass cylinder capping apparatus, a support for a cylinder, an arm for disposition close to the opposite side of the cylinder from said support, a conductor carried by the arm and adapted for holding a wire against said cylinder, a guide pivoted on said arm so that one of its ends may be disposed in proximity to the point where said conductor holds the wire against said cylinder, and a plurality of guide sheaves carried

by the pivoted guide and adapted to receive said wire to facilitate the tightening of the wire around the cylinder by applying a pull thereon.

2. In a glass cylinder capping apparatus, a suitable frame, inverted-arch arms secured at corresponding ends to the frame and projecting laterally therefrom to form a horizontal support for a glass cylinder, a pivoted arm projecting laterally from the frame and adapted at its free end to overlie the cylinder, a conductor plate secured to and projecting from said arm and adapted to rest upon the cylinder, and provided with an eye adjacent the latter, an insulation plate on said conductor plate, a guide pivoted to said arm and adapted to abut at its lower end against said insulation plate, a plurality of guide sheaves mounted in said arm, one of said guide sheaves being located at the end of the guide which abuts said plate, electric current feed wires connected respectively to said conductor plate and said guide, and a wire for encompassing the cylinder and extending at one end through the eye of said conductor plate and secured at such end to the latter, and extending at the other end slidingly over said sheaves; said wire extending over the sheave adjacent the conductor plate, at the side of said sheave in proximity to the eye of the conductor plate.

3. In a glass cylinder capping apparatus, a support for a cylinder, comprising standards, a horizontal bar mounted on said standards, laterally projecting inverted-arch arms secured at corresponding ends to said bar, means cooperating with said arms and the standards for preventing downward movement of the former, lugs projecting rigidly upward from said bar, a rod slidably mounted in said lugs, laterally projecting arms pivoted on said rod and projecting laterally therefrom to move in vertical planes to permit a glass cylinder to be placed on said first-named arms, and to overhang said glass cylinder, and means mounted on and at the outer end of each of said pivoted arms for holding a wire encompassing said cylinder.

In testimony whereof, I affix my signature.

WILLIAM WESTBURY.
